(57) **CLAIM**

The ornamental design for a hand-held laser, as shown and described.

DESCRIPTION

FIG. 1 is a side view of a hand-held laser showing my new design.

FIG. 2 is an opposite side view of the hand-held laser as shown in FIG. 1.

FIG. 3 is a bottom view of the hand-held laser.

FIG. 4 is a top view of the hand-held laser.

FIG. 5 is an enlarged left end view of the hand-held laser as shown in FIG. 1; and,

FIG. 6 is an enlarged right end view of the hand-held laser as shown in FIG. 1.
